UNITED STATES PATENT OFFICE

GEORGE P. EDMONDS, OF CHICAGO, ILLINOIS, ASSIGNOR TO G & W ELECTRIC SPECIALTY COMPANY, OF CHICAGO, ILLINOIS, A CORPORATION OF ILLINOIS

ELECTRICAL CONNECTER

Application filed September 4, 1926. Serial No. 133,604.

My invention relates to improvements in electrical connectors and more particularly to connectors for the top of potheads.

My improvement has to do with means forming a terminal for an insulated conductor such as a pothead which will permit an electrical conductor to be readily connected thereto or disconnected therefrom, and of a structure to serve as means for maintaining 10 an insulating bushing, a cap, and a conductor forming the pothead, in assembled relation, the means being further provided with a portion for abutting and overhanging a portion of the cap to effect a seal and protecting collar for excluding moisture and dirt from the interior of the bushing, and further the provision of a cap for the bushing made of insulating material to assure safe electrical clearance, this last feature being especially advantageous when used 20 on a multiple outlet bushing member.

One of the objects of my invention is to provide a terminal for the insulated end of a conductor which will permit the connection 25 or disconnection of a cable readily without disturbing the pothead assembly.

Another object of my invention is to provide a terminal for an insulated conductor such as a pothead which will permit a cable 30 to be readily connected or disconnected without exposing the interior of the pothead structure to moisture, dirt or detrimental effects.

Another object of my invention is to provide in the combination of an insulating bushing and conductor therefor, a cap nut adjustably connected to the outer end of the conductor in a manner to hold the conductor under tension and centrally disposed in the bushing and provided with a skirt portion 40 adapted to abut and overhang an annular protrusion or collar surrounding the opening through said cap, the cap being likewise provided with a portion for abutting and overhanging the bushing, both arrangements 45 effecting a seal and means protecting the joints between the assembled parts.

A further object of my invention is to provide a connector of the above described type 50 embodying all the advantages set forth in the above stated objects, in which the cap posi-

tioned on the end of the bushing serving to support the cap nut is formed of an insulating material.

These and other objects are accomplished by means of the arrangement disclosed on 55 the accompanying sheet of drawings, in which—

Figure 1 is an elevation in cross-section disclosing the internal structure of my improved electrical connector; and 60

Figure 2 is a top plan view of Figure 1.

The various novel features of the invention will be apparent from the following description and drawings and will be particularly pointed out in the appended claims. 65

Referring to the drawings, it will be noted that my invention is an improvement in potheads comprising a support 10 adapted to be attached as desired by means of screws or the like inserted through openings 11 and provided with a cylindrical body portion 12 receiving in its upper end an insulating bushing 13 preferably but not necessarily provided on its outer surface with petticoats or fins 14, the bushing being attached to the support in any suitable manner, such as, for instance, by cement 15, the upper end of the support resting against the packing ring 16 positioned in a groove 17 provided in the bushing. Extending into the support and bushing is a cable, designated generally 18, suitably wrapped with insulating material 19 and enclosed in a casing 20. The cable is of less diameter than the interior of the bushing in order to provide a space, which is filled 80 with an insulating oil when the structure is completely assembled. The other end of the body portion 12 of the support is provided with an abutment 21 adapted to receive the threaded packing ring 22, the ring being maintained in seated relation by threaded engagement, as at 23, with annular element 24 carried by the casing by means of the clamp 25 connected by bolts 26 to the ears or preferably circular flange 27 integral with the casing. Positioned between the annular element 24 and the packing ring 22 is a packing gland 28 constructed to slide relative to these elements when the packing ring is tightened, 85 in a manner to compress the packing mate- 90

100

rial 29 to seal the conductor opening in the end of the pothead assembly. It will be appreciated that such an end construction forms a very compact and efficient stuffing box for the end of the body portion 12.

The other end of the insulating bushing is bored as at 30 to provide a shoulder 31 on which is mounted a centering ring 32 cemented as at 33 to the internal surface of the bushing. The end of the conductor 18 is exposed as at 34 and is connected as by soldering or any other suitable method in the recess 35 formed in one end of a connector 36, the connector being provided with a collar 37 abutting internally, the centering ring 32, so as to be held centrally disposed thereby. On the outer end of the bushing a cap 38 of insulating material is mounted provided with a bore 39 of greater diameter than the connector 36 so that the cap will be spaced therefrom, and further provided with a depending circumferential flange adapted to overhang the end of the bushing, the packing 40 being interposed between the bushing and the cap between their points of contact. On the outer side of the cap 38 an annular protrusion or collar 45 surrounding the bore is provided. The connector 36 which extends beyond the cap is threaded as at 41 in a manner to receive the cap nut or hood nut 42, the nut having an annular lateral extension 43 adapted to abut the protrusion 45, the extension being provided with an overhanging circumferential flange 44 which may be provided with two engaging shoulders, the packing 46 being introduced between the points of contact. The nut 42 presents a smooth cylindrical surface 47 adapted to receive the clamping lug 48, the packing ring 49 being positioned between the clamping lug and the annular flange on the nut. The clamping lug comprises a split annular portion 50 adapted to surround and tightly engage the nut 42, clamping action being effected by the bolt 51 threaded through lugs at the end of the split annular, and the recessed member 52 in which the end of a cable is soldered.

In operation, my device is attached to any suitable supporting means in a desired manner, the parts being assembled as above described, the connection being effected by placing the cable lug 48 over the terminal end or cap nut 42, the bolt 51 being then turned to clamp the cable in fixed relation. When it is desired to disconnect the cable, it is merely necessary to loosen the bolt 51 and lift the lug 48 from the terminal nut. The advantages of this structure can be readily seen in that it permits a connection and disconnection of the cable by a very simple operation and one which does not necessitate an interference with the assembly of the terminal as a unit, thus eliminating the danger of moisture or dirt or other detrimental substances entering the interior of the structure and in-

fluencing the parts therein. The overhang provided by the annular flange on the nut together with the packing amply protects the joint between these parts, and the cap likewise seals the joint between the cap and bushing by virtue of its structure and the packing 40.

It can be further seen that by the provision of the cap of insulating material, a safe electrical clearance is provided which is especially useful in a multiple outlet bushing construction, thereby eliminating the use of the extremely large insulating bodies necessary when metal caps are used to provide proper clearance between the live parts of the cap 80 and the connector.

I claim:

1. In a pothead connector, the combination of a bushing having a support attached to one end and a cap at its other end, a cable 85 extending into the support and bushing having means abutting the support, a connector attached to the end of said cable and extending through said cap, and a cap nut adjustably connected to the end of said connector 90 and having a portion abutting said cap whereby when the cap nut is tightened the cable and connector are placed under tension between the two abutments so as to be fixed in position.

2. In a device of the character described, the combination of a support, a bushing supported thereby, a cable extending into said support and bushing and provided with means for closing the bottom of said support, insulating means disposed around said cable, a conductor disposed in the top of said bushing provided with spacing means co-operating with said bushing, said conductor being fixedly attached to said cable and provided with actuating means for causing the first mentioned means to have non-leaking engagement with said support.

3. In a device of the character described, the combination with a support, a bushing 110 supported thereby, said support and bushing having a bore therein, a cable disposed therein and provided with means for closing said bore, insulating means in said bore surrounding said cable, centering means supported 115 by said bushing, a conductor extending therethrough fastened to the cable and provided with a collar for sliding engagement with the centering means insuring equal insulation around said cable, and actuating means for 120 said conductor to insure a non-leaking closure between said first named means and the bore.

4. In a device of the character described, the combination with a bushing, of an insulating cap therefor provided with a flange adapted to protect the top of said bushing, a cap nut provided with a flange adapted to protect a portion of said cap and having a thimble for cable lug attachment, a cable 130

conductor disposed within said bushing and provided with a collar, and a centering device within said bushing having engagement with the collar, whereby said conductor is positioned for proper association with said cap nut.

Signed at Chicago, Illinois, this first day of September, 1926.

GEORGE P. EDMONDS.
